T. RUBIN.
CAR DOOR.
FILED APR. 22, 1922.

UNITED STATES PATENT OFFICE.

TONY RUBIN, OF NEW YORK, N. Y.

CAR DOOR.

Application filed April 22, 1922. Serial No. 555,968.

To all whom it may concern:

Be it known that I, TONY RUBIN, a citizen of the United States, residing at New York city, in the county of New York and State of New York, have invented certain new and useful Improvements in Car Doors, of which the following is a specification, reference being had to the accompanying drawings.

10 This invention relates to certain improvements in sliding doors and has relation more particularly to a device of this general character especially designed and adapted for use on freight cars and it is an object of 15 the invention to provide a novel and improved door of this general character comprising two sections, said sections having sliding movement one independently of the other into either open or closed position.

20 Another object of the invention is to provide a novel and improved device of this general character comprising an upper and lower section each having sliding movement one independent of the other and wherein 25 the doorway is intersected by a beam provided with means to afford a guide for each of the sections of the door, said beam being movable, when desired, to the upper portion of the door opening whereby provision 30 is made to permit articles of a relatively large size to be placed within the car body when the occasions of practice may require.

Furthermore, it is an object of the invention to provide a novel and improved door comprising separable sections each having independent movement together with guide and supporting means for each of said sections, said means being slidably positioned 40 between the jambs of the door opening and movable when required into an inoperative position together with means for locking said member in operative position.

The invention consists in the details of 45 construction and in the combination and arrangement of the several parts of my improved sliding door whereby certain important advantages are attained and the device rendered simpler, less expensive and 50 otherwise more convenient and advantageous for use, as will be hereinafter more fully set forth.

The novel features of my invention will hereinafter be definitely claimed.

55 In order that my invention may be the better understood, I will now proceed to de-

scribe the same with reference to the accompanying drawings, wherein:

Figure 1 is an elevational view illustrating a car door constructed in accordance with 60 an embodiment of my invention, one of the door sections being in open position,

Figure 2 is an enlarged fragmentary view partly in section and partly in top plan, illustrating in detail the holding means at 65 one end portion of the beam,

Figure 3 is a view partly in section and partly in elevation of the structure shown and illustrated in Figure 2, and

Figure 4 is a sectional view taken substantially on the line 4—4 of Figure 3.

As disclosed in the accompanying drawings, D denotes a door opening of a conventional type employed in connection with freight cars or the like and with which is 75 associated my improved door. My improved door comprises two sections 1 and 2 of metal or other solid material, each of said sections being adapted to have sliding movement lengthwise of the car so that the 80 same can be adjusted into either closed or open position with respect to the opening D. The lower door section 1 has its bottom edge riding upon the guide rollers 3 suitably secured to the adjacent side wall W 85 of the car while the upper marginal portion of said lower door section 1 has sliding engagement within a trackway 4 secured to the adjacent side wall W and to one side of the door opening D. The upper 90 door section 2 is slidably engaged within the trackways 5 also secured to the adjacent side wall of the car to one side of the door opening D. The upper trackway 5 extends over the upper portion of the opening D so that the upper section 2 may have 95 the desired or requisite sliding movement.

B denotes a horizontally disposed beam positioned between the jambs 6 of the door opening D, the opposite end portions of said beam B extending between the vertically disposed plates 7 secured to the opposite sides of the upper portions of the jambs 6 and extending to substantially the tops thereof.

Secured to the outer face of the beam B 105 are the trackways 4' and 5' which, when the beam B is in its lowermost position, aline, respectively, with the trackway 4 and the lower trackway 5 so that with the beam in its lowered position the door sections 1 and 110 2 may have sliding movement into closed position with respect to the opening D.

In loading or unloading the car either of the door sections 1 or 2 may be slid into open position as the occasions of practice may prefer. In the event the load consists of grain, coal or other material capable of flow, I provide the lower portion of the door section 1 with a supplemental door opening 9 which, when the section 1 is in closed position, is closely positioned to the bottom of the car. Associated with the door opening 9 is a door 10 herein disclosed as having upward swinging movement when moved into open position. Associated with the door 10 and the portion of the section 1 defining the lower portion of the door opening 9 are co-acting locking members 11 which may be of any type preferred.

The downward movement of the beam B is limited by the stops 12 suitably secured to the jambs 6 and with which the under face of the beam B at the extremities thereof contacts.

When the beam B is at the limit of its downward movement the same is held against upward movement by the sliding bolt 14 mounted upon the opposite end portions of the beam B and each of said bolts being engageable with a suitable keeper 15 in the adjacent jamb 6.

Extending outwardly from the inner face of the beam B adjacent the opposite ends thereof are the eye members 16, each of which is adapted to be engaged, when the beam B is at the limit of its upward movement, by hook members 17 supported by and depending from the top piece or crown 18 of the frame of the door opening D.

It is to be understood that before the beam B is raised upwardly the door sections 1 and 2 are first moved into open position or in a position to one side of the door opening.

When the door sections 1 and 2 are in closed position the same are held closed by the co-acting locking members 19.

From the foregoing description it is

thought to be obvious that a sliding door constructed in accordance with my invention is particularly well adapted for use by reason of convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

In combination with a wall provided with a door opening, supporting means positioned above and below the opening and extending to one side thereof, supporting means positioned to one side of the door opening at a point between the ends of the opening, sliding door sections engaged with said supporting means, each of said sections being slidable to overlie a portion of the opening or to position at one side thereof, plates secured to the opposite sides of the wall at the upper portion of each side of the opening and extending within the opening to provide guideways, a beam positioned within the opening and extending thereacross, the extremities of the beam engaging between the plates, said beam being movable toward an end of the opening, said beam having supporting means registering with the second named supporting means when the beam is at the limit of its downward movement in one direction within the opening, strips disposed transversely of the guideways with which the extremities of the beam contact to limit the downward movement of the beam, and means carried by the beam for locking said beam in the last named position.

In testimony whereof I hereunto affix my signature.

TONY RUBIN.
